UNITED STATES PATENT OFFICE

2,596,979

DEHUMIDIFIER

James W. Case, Fairfax, Va.

Application January 11, 1950, Serial No. 138,041

2 Claims. (Cl. 183—4.5)

(Granted under the act of March 3, 1883, as
amended April 30, 1928; O.G. 757)

1

The present invention relates to dehumidifying devices and more particularly to devices for removing and excluding moisture from chambers or containers such as casings for instruments whereby fungus growth and corrosion due to moisture may be inhibited. A feature of said invention resides in the provision of novel means for reactivating moisture adsorbing materials employed therewith.

Heretofore dehumidifying devices for such use have comprised a desiccant, such as silica gel or the like, suitably supported to permit air circulation therethrough. Such desiccant must be frequently replaced. This is objectionable and such dehumidifiers are particularly unsatisfactory for use with aircraft instruments since the rapidly fluctuating temperature and pressure conditions to which such instruments are subjected increase air circulation and accelerate saturation of the desiccant.

To avoid such difficulties it has heretofore been necessary to enclose delicate aircraft instruments in hermetically sealed cases. It has further been necessary to construct the instrument cases of materials sufficiently strong to withstand pressure extremes so that the cases will not be crushed or warped. This increases the weight of the instruments, and difficulty is encountered when the cases must be opened to service the instrument enclosed therein.

Hence, an object of the present invention is to provide a new and improved type of dehumidifier for removing and excluding moisture from instruments.

Another object of the invention is to provide a dehumidifier for substantially closed bodies wherein means are provided for increasing the effective life of a desiccant employed therewith before said desiccant must be reactivated.

Another object of the invention is to provide an instrument dehumidifier having in combination therewith a breather tube which is so arranged and constructed as to initially exclude a substantial portion of the moisture suspended in the air breathed through the tube.

Another object of the invention is to provide means for reactivating regenerable desiccants employed in dehumidifiers.

Other objects and their attendant advantages will become apparent as the following detailed description is read in conjunction with the accompanying drawings wherein:

Fig. 1 is a cross-sectional view partly in elevation showing one embodiment of the present invention applied to an instrument case;

2

Fig. 2 is a transverse section partly in elevation taken on a line substantially corresponding to line 2—2 of Fig. 1; and

Fig. 3 is a schematic view of a circuit incorporated in the device of the present invention.

Referring now to the drawings in detail the numeral 10 designates an instrument case which is provided with an opening 11 over which is positioned a dehumidifier assembly 12. The latter comprises a hollow cylindrical housing 13 which may be secured by means of a suitably sealed flange 14 to the exterior wall of the case. Within the housing 13 and spaced from the interior wall thereof is a desiccant container 15 which may comprise a pair of spaced concentric cylindrical perforated shells 16 and 17 which are adapted to contain between their adjacent surfaces a regenerable desiccant 18 such as silica gel or the like. If desired, the desiccant 18 may be molded in the form of a suitable cylinder and substituted for the container 15 provided the desiccant is a moldable type such as activated alumina. Seals 19 and 20 are located at opposite ends of the container 15 to provide a sealed space 21 from which the circulating air must pass through the desiccant.

A breather tube 22 which is exposed to the atmosphere at one end 23 leads a substantial distance into the housing 15 and terminates at 24 in the space 21 as shown. The breather tube 22 forms an important feature of the present invention since I have found that the amount of moisture that will diffuse through such a tube is a function of the length and the cross-sectional area of that tube. I have found further that by providing a breather tube 22, having a length more than ten times its inside diameter, in this dehumidifier, atmospheric moisture is substantially prevented from entering the instrument case 10 during periods when no breathing occurs through the tube, such as during static atmospheric conditions, while an instrument 10 may be stored or held in a standby condition. I have found further that, as inbreathing occurs into instrument 10, as would happen when an aircraft descends from a high altitude to a low altitude, a substantial portion of the atmospheric moisture will be completely removed as the air passes through the desiccant 18 and enters the instrument case 10. Hence, by providing a dehumidifier with a breather tube of proper dimensions as aforesaid, an instrument with which the dehumidifier may be used can breathe naturally in accordance with changes in ambient temperature and pressure conditions and still be pro-

tected against atmospheric moisture at all times.

Means for reactivating the desiccant are provided and this means will now be described. Embedded in the desiccant 18 is an electric heating element 25 which may comprise a stretched coil of resistance wire, appropriately sheathed as shown, or bare. Electrically connected in parallel with the heating element 25 is a blower motor 26 (Fig. 3), adapted to drive a blower 27 which is connected by a suitable passageway 28 with the central hollow portion 29 of the dehumidifier as shown. Mounted on the blower 27 is an outlet valve 30 which is adapted to open only during the outflow of air therethrough.

When it becomes necessary to reactivate the desiccant 18, a switch means 32 is operated, either manually or automatically by means of a humido-stat, time switch, or the like, to simultaneously energize the heating element 25 and the blower motor 26. Any convenient current source may be used, for example, a battery 31 or an ordinary alternating or direct current outlet. The heat generated by the element 25 will cause desorption of the desiccant 18 and the blower 27 will draw reactivating air from the outside atmosphere through the dehumidifier and discharge the liberated moisture to the atmosphere.

When the blower is started, air from the outside atmosphere is drawn through the breather tube 22 to the space 21, which serves as a manifold for equal distribution of the atmospheric air to the desiccant 18, thence through the desiccant 18 where temperature rise permits the air to absorb moisture being liberated from the desiccant, thence into the space 29 and again to the outside atmosphere via the passageway 28, the blower 27 and outlet valve 30. Thus a rapid reactivation of the desiccant will be accomplished without removing it from the dehumidifier and without exposing the instrument case 10 to the moisture present in the dehumidifier during the reactivating process.

It should, of course, be noted that, if desired, the reactivating means aforesaid may be connected directly in the power circuit of such electrical instrument as may have been housed in the case 10. Then while the instrument is in use, (electrically energized) the desiccant will maintain the delicate parts of the instrument dry and operable and the reactivating means will maintain the desiccant 18 in an activated state. Later, should a static condition occur, as when the instrument is put in storage, is shipped or assumes a standby condition, immediate protection is available due to the adsorption capacity of the desiccant 18.

Obviously modifications and variations of the present invention are possible in the light of the above teachings. It is therefore to be understood that within the scope of the appended claims the invention may be practiced otherwise than as specified.

The invention described herein may be manufactured and used by or for the Government of the United States of America for governmental purposes without the payment of any royalties thereon or therefor.

What is claimed is:

1. A dehumidifying device for controlling moisture conditions within a substantially closed chamber without preventing ingress of outside air comprising; a housing, said housing having an air admitting aperture, a desiccant within the housing arranged in the form of a barrier so as to divide the housing into two concentric chambers, a tube communicating with said aperture said tube being of a length at least ten times its internal diameter, the inner end of said tube terminating in one of said chambers, the other of said chambers being adjacent and in direct communication with the space in which dehumidifying conditions are to be maintained.

2. A dehumidifier for controlling moisture conditions within an enclosed space comprising a housing, a desiccant within the housing, said desiccant dividing the housing into two concentric chambers, an air ingress port comprising a moisture inhibiting diffusion tube of a length at least ten times its internal diameter, one end of said tube extending through the housing to communicate with the outside air and the other end terminating within one of said chambers, the other of said chambers being in direct communication with the enclosed space to permit the diffusion of dehumidified air therebetween, and means for reactivating the desiccant.
